No. 688,983.

Patented Dec. 17, 1901.

L. C. BABCOCK.
ELEVATOR.

(Application filed Apr. 27, 1901.)

(No Model.)

UNITED STATES PATENT OFFICE.

LUCIEN C. BABCOCK, OF BROOKLYN, NEW YORK.

ELEVATOR.

SPECIFICATION forming part of Letters Patent No. 688,983, dated December 17, 1901.

Application filed April 27, 1901. Serial No. 57,659. (No model.)

To all whom it may concern:

Be it known that I, LUCIEN C. BABCOCK, a citizen of the United States, residing in the borough of Brooklyn, in the city and State of New York, have invented a certain new and useful Improvement in Elevators, of which the following is a specification.

The invention is adapted to serve either for freight or passengers. I will describe it as serving for freight in a warehouse. The weight of the car may be partly balanced by ordinary means, if desired.

I have in patents to me—one dated March 21, 1899, No. 621,313, and another dated June 5, 1900, No. 651,095—set forth means for raising and lowering the car by means of large straight tubes extending up and down on opposite sides of the elevator-well, each having a continuous narrow slot on the inner side, through which extends a flat web of steel connecting from the car to a piston, which nicely fills the tube, with efficient means for supplying air at the required pressure in the base of each tube, so that the descent may be controlled and the car be elevated by the pressure of the air under the pistons. The present invention employs the same structure so far as yet described.

According to the present invention the slot is fortified by clips carried by the car and is covered on the inside by a nearly stationary instead of a traveling band. The band extends continuously from the top to the bottom with only sufficient slack to allow the required manipulation as the car moves up and down. This construction avoids friction.

I provide a chisel-ended device, which I will term a "plow," on each tube to move up and down with the car and aid in ejecting each band from its seat and allow its smooth return as the car moves up and down. I fork the flat web after it has extended outward from the car quite through the narrow slot, and do this either by forging the steel in such shape or by riveting or bolting on parts to connect with the piston-rods and allow the latter and their attached pistons to support the car. I employ wheels to properly guide the slack portion of the band while it is making its detour in the tube while the car is passing any given point.

The following is a description of what I

consider the best means of carrying out the invention.

The accompanying drawings form a part of this specification.

Figure 1 is a vertical section. The remaining figures are on a somewhat larger scale. They are all horizontal sections of a portion in Fig. 1. Fig. 2 is on the line 2 2. Fig. 3 is 60 on the line 3 3. Fig. 4 is on the line 4 4. Fig. 5 is on the line 5 5. Fig. 6 is on the line 6 6. Fig. 7 is on the line 7 7. Fig. 8 is on the line 8 8, and Fig. 9 is on the line 9 9 in said Fig. 1.

Similar letters of reference indicate corresponding parts in all the figures where they appear.

A' A' are the tubes, each having a longitudinal opening *a* on the side toward the car. These tubes and their contents are counterparts each of the other, and a description of one will serve for both.

B is the car, and B' a plane web of steel, thin and flat like a saw-plate, extending outward from the car through the narrow aperture *a* into the interior of the tube, where it is thickened and branched and strongly united to the two piston-rods, to be presently described.

B² is a piston connected to the car by piston-rods B³ and the web B'. There is a liberal opening in the line of the axis of the cylinder. A channel a' is provided in the interior of the tube, so arranged that when the band C is home in the bottom of that channel the aperture *a* is closed. I provide sufficient slack in the band to allow it to make a slight detour where the car passes it in moving upward or downward.

B⁴ is a flat piece, which I will call the "plow," 90 having chisel-shaped ends extending up and down in the tube, fitting in the channel a' along a considerable space, which is left uncovered by the absence of the flexible band C where it is making its detour. This band 95 C does not move up and down with the car, but in some respects corresponds to the band similarly marked in my previous patents. According to my present invention it is secured to the tube at the top and bottom and 100 lies for most of its length flat in the shallow channel a', but with considerable slack.

The piston B² is provided with packing (not shown) to allow it to match in the interior of

the tube, so that it is practically air-tight and moves easily, so that a sufficient pressure of air maintained below will press upward against the piston to induce the ascent and to moderate the descent.

Provision is made for allowing the air to pass freely through liberal apertures in each piston at will. This is obtained by a grated valve-seat B^6 in the piston and a corresponding grated valve G , fitting on the under side thereof. This valve is operated through a packed stem G' and connections from a hand-lever F , operated by the attendant in the car. The link E' , extending in the opposite direction to operate the valve in the opposite piston, is connected to give a corresponding motion. The turning of the lever in one direction opens both valves and turning in the opposite direction closes both.

It will be noted that the parts B^2 , which I term "piston-rods," are each flat or slightly curved in cross-section and set well out toward the periphery of the piston B^2 . The bottoms of the tubes $A' A'$ are united by a tube A and the tops by a tube A^2 . The lower tube A connects to a reservoir A^3 of compressed air, which is kept supplied by an air-pump. (Not shown.) The upper tube A^2 communicates with the open air.

The turning valve W turns on an axis W' and is controlled by the attendant through the ordinary cord K , running over a pulley V' at the top and under a pulley V^2 at the bottom. The corresponding valve V in the upper tube A^2 is similarly operated by a corresponding cord L , as shown in my patent of June, 1900, above referred to. This should be closed when the car is allowed to descend.

The provisions for temporarily dislodging the band C from its seat across the aperture a to allow the thin plate B' to extend through the aperture a along the part which is at the level of the car and for returning the band to its place again in the channel a' after the car has passed are as follows:

M M are the wheels carried on pins set in the pair of piston-rods B^3 . The band C is deflected outward, so as to extend around on the outside of these wheels, running easily through a tight-fitting slot provided in the piston B^2 and properly packed.

Q Q are wheels also carried between the piston-rods B^3 and arranged to press the flexible band C tightly into its seat in the groove a' . The space between each wheel Q and the adjacent chisel-shaped end of the plow is limited. It is in theory only just sufficient to allow the passage of the band. As the car moves downward the lower chisel-shaped end of the plow B^4 insinuates itself between the band and its seat and dislodges it out of the groove a' . The band after being thus displaced is guided outside of the wheel M , and as the car descends the band is again returned to its seat above the plow B^4 and is pressed again home in its place in the groove a' by the upper wheel Q . When the car rises, a

corresponding movement of the band occurs in the opposite direction.

It will of course be understood that the only motions of the band are the movements of a portion at a time horizontally away from the car and thus away from its seat-groove a' and back again as the car passes.

There is a tendency of the aperture a to open too wide by reason of the pressure of the inclosed air. This is liable to be further increased by the pressure of the tightly-packed piston B^2 and other parts, especially if there is any jolting from any cause as the car is passing. I defend against any too great opening of the aperture at points near the car by embracing the ridges or flanged edges in clips B^7 carried with the car and thus fortifying it by pressing fairly on the two outer faces of the ridges. (See Fig. 9.)

The following is one of the methods, perhaps the best, in which compressed air can be employed in my invention for elevating the car: While the car is at the lower terminal the valve V at the upper end A' is closed and the valve G in the piston B^2 is opened sufficiently to permit the compressed air to fill the tubes to any required extent. Then close the piston-valve G , and in order to ascend open the upper valve V to the extent required for either a quick or a modified ascent, closing it some two or more feet before the arrival of the car at any desired stopping-point.

Modifications may be made without departing from the principle or sacrificing the advantages of the invention. Some of the features of this invention may be used without others. I can omit the clips B^7 . I can omit the plow B^4 and depend on the wheels M Q Q or can omit the wheels and after dislodging the band from its channel can lead the band about and return it by other means. I prefer the whole used together and proportioned and arranged about as shown.

I claim as my invention—

1. In an elevator having tubes each with a continuous longitudinal aperture receiving an extension from the car and provisions for operating by air-pressure in such tubes, a flexible band C arranged to cover the joint, in combination with means carried with the car for displacing and returning such band, all substantially as herein specified.

2. In an elevator having tubes each with a continuous longitudinal aperture receiving an extension from the car and provisions for operating by air-pressure the tubes A' each formed with a projecting ridge extending up and down on each side of the aperture a and inclosing a channel a' , in combination with one or more clips B^7 carried by the car and arranged to aid in holding the joint to the proper limited width, all substantially as herein specified.

3. In an elevator having tubes each with a continuous longitudinal aperture receiving an extension from the car and provisions for

operating by air-pressure in such tubes, a flexible band C in each arranged to cover such aperture on the inside, permanently secured at each end with a sufficient excess of length, 5 and the plow having wedge-formed ends carried with the car arranged to aid in detaching the band from its seat and allowing its return as the car moves up and down, all substantially as herein specified.

10 4. In an elevator having tubes each with a continuous longitudinal aperture receiving an extension from the car and provisions for operating by air-pressure in such tubes, a flexible band C arranged to cover such aperture 15 on the inside permanently secured at each end with a sufficient excess of length, and the wheels M Q Q carried with the car arranged to aid in detaching the band from its seat and returning it again and pressing it home to 20 form a tight joint as the car moves up and down, all substantially as herein specified.

5. In an elevator having tubes each with a continuous longitudinal aperture receiving an extension from the car and provisions for 25 operating by air-pressure in such tubes, a flexible band C arranged to cover such aperture

on the inside permanently secured at each end with a sufficient excess of length and the plow B⁴ having wedge-formed ends, and the wheels M Q Q carried with the car arranged 30 to aid in detaching the band from its seat and returning it again and pressing it home to form a tight joint as the car moves up and down, all substantially as herein specified.

6. In an elevator having tubes each with a continuous longitudinal aperture receiving an extension from the car and provisions for operating by air-pressure in such tubes, the webs B' branched within the tubes and piston-rods B³ and liberally-apertured pistons B², 40 in combination with each other and with a grated valve-seat B⁶ and a corresponding grated valve G and connections for operating the latter by the attendant in the car, all substantially as herein specified. 45

In testimony that I claim the invention above set forth I affix my signature in presence of two witnesses.

LUCIEN C. BABCOCK.
